United States Patent Office

Des. 204,890
Patented May 24, 1966

204,890

GOLF PUTTER

Robert J. Mader, 1607 Hickory St., Torrance, Calif.

Filed June 14, 1965, Ser. No. 85,729

Term of patent 14 years

(Cl. D34—5)

FIG. 1 is a perspective view of the putter, showing my new design,

FIG. 2 is a top plan view of the putter head, and

FIG. 3 is an end elevation view of the putter head.

The shaft has been omitted from FIGS. 2 and 3 for convenience of illustration.

The face portion of the club not shown is plain and unornamented.

I claim:

The ornamental design for a golf putter, as shown and described.
